UNITED STATES PATENT OFFICE.

HARRISON J. L. FRANK AND LEON H. FRANK, OF WHEELING, WEST VIRGINIA.

PANEL-BOX.

1,169,390.

Specification of Letters Patent. Patented Jan. 25, 1916.

Application filed February 20, 1912. Serial No. 678,877.

To all whom it may concern:

Be it known that we, HARRISON J. L. FRANK and LEON H. FRANK, citizens of the United States, and residents of Wheeling, 5 in the county of Ohio and State of West Virginia, have invented a new and useful Improvement in Panel-Boxes, of which the following is a specification.

Our invention relates to panel boxes, and 10 it has for its object to provide a box especially adapted to contain panels bearing switches having operating handles that are movable longitudinally in a direction perpendicular to the panel, the said handles projecting through the cover to permit of operation of the switches from the exterior of the panel box.

A further object of the invention is to provide a mounting for the covers of such panel 20 boxes which will permit of their being conveniently and readily opened or placed at the sides of the boxes without disturbing the switches or detaching the covers from the boxes.

25 A still further object is to provide means for locking the switches contained within the panel boxes in either their open or their closed positions.

Our invention is illustrated in the accompanying drawings, Figure 1 of which is a 30 face view of a panel box embodying my invention, the covers thereof being in open position. Fig. 2 is an end and sectional view of the box of Fig. 1. Fig. 3 is a sectional view of the box of Fig. 1 showing the switches in side elevation. Fig. 4 is an inside view of one of the covers of the box, and Fig. 5 is a sectional view of one of the covers.

40 The box in connection with which the present invention is employed, is of any of the usual and heretofore known constructions, and comprises an outer metallic case or box 1 inclosing a frame composed of 45 insulating side pieces 2 spaced a convenient distance from the sides of the outer box, the said frame surrounding an insulating panel board 3, upon which are mounted bus bars 4 forming parts of the various circuits to 50 be controlled. As here shown, the ends of certain of the bus bars constitute terminal members of switches 5 that serve to connect the same in the proper and desired relations, and that may be of any suitable construction, though they are preferably of the construction shown, which is covered in a sepa-

rate application. Each of said switches comprises two insulating blocks 6 that carry contact members 7 at their extremities, which members are moved into and out of engagement with the ends of the bus bars constituting the circuit terminals by means of a handle 8 that is movable longitudinally in a direction perpendicular to the panel board. The said switches are also so constructed 60 that they are caused to move with a snap action toward both their closed and open positions, such a switch being set forth in our co-pending application Serial No. 678,878. The switch handles project through 70 apertures in the covers 9 of the box to permit of operation of the switches from the exterior of the box while the covers remain in their closed positions, and the handles are provided with slots 20 in the portions thereof that are adjacent to the inner faces of the covers when the switches occupy their open and closed positions respectively.

In order to insure against unauthorized 80 opening and closing of the switches, longitudinally movable locking bars 10 are secured to the inner faces of the covers 9 by means of clips or staples 11 and are provided with apertures or slots opposite the apertures in the covers through which the 85 switch handles also project. Longitudinal movement of the locking bars, for the purpose of causing the portions thereof surrounding the apertures therein to move into and out of the slots in the switch handles, 90 may be effected by rotation of pinions 13, that mesh with racks or teeth 14 upon the edges of the locking bars, and are provided with steins 15 projecting through the covers 95 and adapted to receive a removable operating key 16. Other suitable locking means for the switches may, of course, be employed instead of that illustrated without departing from the spirit of the invention.

The covers 9 are so mounted and secured 100 to the box itself as to permit of readily opening or swinging the same back for inspection of the panel board and switches, the said mounting, as here shown, conveniently comprising a pair of links 18 and 19 at each end of each cover that are pivotally connected together at one end, and are respectively pivotally connected to the box and to the covers at their other ends. While the pivotal points may be otherwise located, 110 if desired, the links are preferably pivoted to the box and to the cover at, and opposite

to, intermediate points of the covers. In opening or swinging back the covers, they are first moved perpendicularly to the face of the panel box until they have cleared the ends of the switch handles, and then they are moved to positions corresponding to that shown in dotted lines in the lower right-hand corner of Fig. 2, these movements being permitted by reason of the employment of the link-form of mounting. While the covers are preferably mounted substantially as shown, it is to be understood that any mounting which will permit of an initial movement of the covers to clear the switch handles and of then swinging them back out of the way is within the spirit and scope of our invention.

We claim as our invention:

1. The combination with a panel box, and 20 a cover therefor, of a switch contained within the box and having a handle that projects through the cover, and a mounting for the cover which permits of moving the same to clear the switch handle and of then moving it to one side while still securing it to the box.
2. The combination with a panel box, and 30 a cover therefor, of a switch contained within the box and having a handle that projects through the cover, a mounting for the cover which permits of moving the same to clear the switch handle and of then moving it to one side while still securing it to the box, and means carried by the cover for locking the switch handle in either its open or closed position.
3. The combination with a panel box, and 40 a switch contained therein having a longitudinally movable operating handle, of a cover for the box having an aperture

through which the handle projects when the cover is in closed position, and links that are pivoted to each other and are also respectively pivoted to the box and to the cover, thereby permitting the cover to move to 45 clear the switch handle and then to move to one side of the box.

4. The combination with a panel box and a switch contained therein having a longitudinally movable operating handle, of a 50 cover for the box having an aperture through which the handle projects when the cover is in closed position, pivotally-connected links that are also respectively pivoted to the box and to the cover, and a 55 device carried by the cover for locking the switch in either its closed or its open position.

5. The combination with a panel box, and a switch contained therein having a longitudinally movable operating handle, the said handle being provided with slots corresponding respectively to the open and closed positions of the switch, of a cover for the box having an aperture through which the 60 handle projects when the cover is in closed position, pivotally-connected links that are also respectively pivoted to the box and to the cover, and a locking device carried by the cover that is movable into and out of 65 the slots in the switch handle.

In testimony whereof, we have hereunto subscribed our names this 9th day of February, 1912.

HARRISON J. L. FRANK.
LEON H. FRANK.
